UNITED STATES PATENT OFFICE.

GEORGE W. RISTINE, JR., OF CHICAGO, ILLINOIS, ASSIGNOR TO PRESSED STEEL CAR COMPANY, OF PITTSBURGH, PENNSYLVANIA, A CORPORATION OF NEW JERSEY.

CAR-ROOF.

1,309,777.

Specification of Letters Patent. Patented July 15, 1919.

Application filed May 11, 1917. Serial No. 168,367.

To all whom it may concern:

Be it known that I, GEORGE W. RISTINE, Jr., a citizen of the United States, residing in Chicago, in the county of Cook and State 5 of Illinois, have invented certain new and useful Improvements in Car-Roofs, of which the following is a specification.

This invention relates to an improvement in car roof construction, an object being to 10 provide a roof having a maximum of strength with a minimum weight and which will be simple in construction and capable of being manufactured at low cost.

Another object of the invention is to provide an improved carline which can be made of a commercial section or pressed shape, to which the roof plates are adapted to be attached by resilient means and without the use of rivets passing through the roof plates.

20 Another object of the invention is to provide simple means for the attachment of the roof plates to the carline, which, while forming weather-proof joints between the roof plates and carline, will permit of the 25 easy removal and replacement, when necessary, of such plates.

Another object of the invention is to provide means for attaching the roof plates to the carline in such a manner that such means 30 is so anchored to the side plates, that a large proportion of the strain due to holding the roof plates in contact with the carline is transmitted to the side plates.

Referring now to the drawings in which 35 like reference character refer to like parts, Figure 1 is a plan view of a portion of a car roof embodying the invention; Fig. 2 is a sectional view of the same taken on the line 2-2 of Fig. 1 and Fig. 3 is an end elevation 40 of the same. Fig. 4 is an enlarged sectional view taken on the line 4-4 of Fig. 1, and Fig. 5 is a cross sectional view taken on the line 5-5 of Fig. 1; Figs. 6 and 7 are 45 sectional views of a modification of the invention, which views correspond to Figs. 4 and 5 of the preferred form.

Referring now in detail to the drawings, 1 indicates one of the side plates of the car which may be of any suitable form or construction, but as shown in the drawings are 50 preferably of angular cross section. 2 indicates one of the carlines which extend across the car and are secured to the side plates 1. These carlines may be of any suitable form 55 but are preferably of rolled or pressed chan-

nel form having a horizontally disposed web 3 and vertical flanges 4 which extend upwardly therefrom.

The roof comprises a plurality of plates 5, 5, which rest on the flanges 4 of the carlines and preferably extend continuously across the full width of the car. Each of these roof plates is provided with down-turned end and side flanges 6 and 7 respectively, the end flanges 6 overlapping the side 60 plates when the roof plate is in its proper position on the carline 2, and the side flanges 7 extending into adjacent carlines. The side flanges 7 are provided with perforations 8 at intervals throughout their lengths which are 65 adapted to receive members 9 for fastening the roof plates to the carlines. The members 9 are located within the carlines and between the side flanges 7 of the roof plates, and are slightly bowed or curved, the side portions 70 10 of the members passing through the perforations 8 of adjacent roof plates. The lower portions of the side flanges 7 of the roof plates are doubled upon themselves, so as to provide additional thickness of metal 75 80 and strength in that portion of the flange which is slotted for the ends 10 of the members 9 to pass through.

11 indicates bolts which extend from side to side of the car and are anchored in 85 bracket members 12 which are secured to the side plates 1 at the ends of the carline. Between the bracket members 12 these bolts seat in grooves or recesses 13 formed in the upper surface of the members 9, and when the nuts 90 14 at the ends of the bolts are tightened against the bracket members 12, the tension on the bolts tending to straighten them, produces a downward pressure on the members 9, which engage the side flanges 7 of the roof 95 plates, thus holding the roof plates to the carlines. The curved form of the carline, curving downwardly to each side of the car, insures that water falling in the channel of the carline will be conducted to one or 100 both ends thereof, and permitted to escape through slots or notches 17, 17, which are cut in the end flanges of the roof plates.

In the modification of the invention as shown in Figs. 6 and 7 the transverse bolts 105 11 of the preferred form are omitted, and the carline is provided with a plurality of shoulder bolts 15 which are secured in the web of the carline and are adapted to extend through the members 9, the upper ends of 110

these bolts being provided with a threaded portion adapted to receive a nut 16, which nut when tightened produces a downward pressure on the members 9, which engage the 5 side flanges 7 of the roof plates, thus holding the roof plates to the carline.

It is to be understood that the members 9 may if desired be made of material having more or less resiliency, thus providing for a 10 greater amount of movement between adjacent roof plates, and a greater amount of movement between the roof plates and the carlines which support them.

It will be noted from the foregoing description that the roof plates are held to the upper frame work of the car without rivets, and also that they are held in such a manner as to permit slight movement between the plates as the car weaves due to uneven track 20 and other service conditions.

Although in the drawings and foregoing description only portions of one carline and the roof plates, and the several parts coöperating therewith are illustrated and described, it will be understood by those skilled in the art that both ends of the carline are substantially alike, and that a railway car roof is composed of a plurality of such parts.

Claims:

30 1. In a car roof, a carline, roof plates supported by said carline and having openings formed therein, members engaging said openings, said members having grooves in their upper surfaces and means engaging said 35 grooves to retain the roof plates on said carline, and means for applying tension to said means.

2. In a car roof, a carline, roof plates supported by said carline and having openings 40 formed therein, resilient members engaging said openings, said members having grooves formed in their upper surfaces, and means engaging said grooves to retain the roof plates on said carline, and means for applying tension to said 45 means.

Copies of this patent may be obtained for five cents each, by addressing the "Commissioner of Patents, Washington, D. C."

3. In a car roof, a carline, roof plates supported by said carline and having openings formed therein, members engaging said openings, said members having grooves formed in their upper surfaces and a rod extending 50 from side to side of the roof, adapted to engage the grooves in said members and retain the roof plates on said carline, and means for applying tension to said rod.

4. In a car roof, side plates, a carline, roof 55 plates supported by said carline and having openings formed therein, members engaging said openings, said members having grooves and a rod extending from side to side of the roof, adapted to engage the grooves in said 60 members and retain the roof plates on said carline, said rod being secured to said side plates, and means at the sides of the roof for applying tension to said rod.

5. In a car roof, a carline of flanged section, roof plates supported by the flanges of said carline, flanges on said roof plates extending between the flanges of said carline and having openings formed therein, members engaging said openings, said members having grooves formed 70 in their upper surfaces and rod means engaging said grooves to retain the roof plates on said carline, and means for applying tension to said rod means.

6. In a car roof, a carline, roof plates supported by said carline, flanges on said roof plates and having portions folded upon themselves and openings formed in said folded portions, members engaging said openings, said members having grooves formed 80 in their upper surfaces and means engaging said grooves to retain the roof plates to said carline, and means for applying tension to said means.

In testimony whereof I affix my signature 85 in the presence of two witnesses.

GEORGE W. RISTINE, JR.
